HYDRAULIC CANE FEED STOP AND LEVELER

Application filed August 22, 1930. Serial No. 477,114.

The present invention relates to improvements in sugar cane crushers and more particularly to improved devices for stopping and regulating the advance of sugar cane in the crusher supply chute.

5 The object of the invention is to provide stop devices in a sugar cane mill for relieving congestion in cane chutes and for regulating the cane feed to maintain a uniform depth of cane in said chute in its travel to the crusher rolls, said devices engaging the contents of said chute at the top and at the bottom thereof.

10 In cane mills, the crusher rolls and the first mill rolls are usually driven together, and in many instances the first mill rolls do not take the feed of the cane coming from the crusher rolls at the same rate of speed, which is due either to change of speed in mills, faulty roll setting, badly worn trash turner plate in the first mill, or change in variety of sugar cane etc. The cane therefore piles up in front of the crusher rolls completely choking them up, and these rolls keep on moving, but no 15 productive action occurs. To clear the mill of this accumulated cane, the services of four or five men with steel hooks with the loss of considerable time, is required, and moreover the steel hooks often become lost in the cane 20 and are carried through the entire mill causing considerable damage to the rolls, and putting the entire mill out of operation, resulting in considerable loss.

To overcome these difficulties, I have provided a power operated cane feed stop and regulator properly located forwardly of the crushing rolls which may be operated by manipulating the handle of a four way hydraulic control valve conveniently located, the 25 operation being rapid and positive.

The inventive features of the improved devices reside in the provision of stop devices, one entering the cane chute from below, and the other engaging the cane in the chute from 30 above, the stop devices being operable in op-

posed directions and simultaneously through appropriate lever and link connections by hydraulic or other power means.

The depth of cane in the chute should at all times be about four feet and to maintain this depth an operator may be stationed at the handle of the four way hydraulic valve to operate it, when necessary, to retard the feed and permit the cane to build up to that depth, after which the cane is released to continue to the crusher rolls.

The invention also includes the provision of stationary cane levelers consisting of downwardly extending arms fixedly spaced on suitable cross members fixed to the sides of the chute.

In the drawings, a preferred embodiment of the device is illustrated, and it will be understood changes in the construction and proportion of parts may be made within the scope of the invention claimed and similar reference characters are employed to designate corresponding parts throughout the several views, in which

Fig. 1 is a side view, partly broken away of a sugar cane mill with my invention applied in operative position and the stop members started to the retarding position.

Fig. 2 is a front view of the cane chute with parts omitted, looking as the arrows 2-2 of Fig. 1, point.

Figs. 3 and 4 are detail views of a power cylinder employed.

Referring to the drawings in detail, 10 designates the mill frame in which crusher 80 rolls 11, are journalled in suitable bearings 12 and are driven with the first mill rolls 13 in any approved manner.

Supported on a post 14 or the like is an arcuate casting 15 forming the mouth of a 85 sugar cane chute 16 which communicates with the crusher rolls 11; the chute has an extension 17, to the first mill rolls 13. The chute 16 has a floor 18, and panelled sides 19, which may be welded or otherwise secured to the 90

sides of the arcuate casting 15; said casting being formed with side bearings 20, (one only being shown) in which a pulley 21 is journalled to support a travelling cane feeding conveyor 22.

3. Located between the sides 19 of the cane chute 16, are cane levelers 23, to level off the incoming cane as it enters the chute from the conveyor.

10 The retarding devices of the invention preferably include a rock shaft 24, extending across the chute 16, with its ends journalled in bearings 25; one end being projected to receive an affixed sleeve 26 formed with a 15 backwardly extending upper arm 27, having its end pivotally connected as at 28, to the upper end of a downwardly and forwardly extending link member 29, which in turn is pivoted as at 30, to the forward end of a lower arm 31 which has a sleeve 32, keyed to a cross rock shaft 33, mounted in suitable 20 bearings 33' and having integral backwardly directed arms 34, pivoted as at 35, to a set of pointed stop pins 36, extending upwardly 25 loosely through holes 37, in the bottom 18 of said chute.

Locked to the cross shaft 24, is a sleeve or sleeves 38, with which a number of arms 39 are associated, and are secured together rearwardly of the shaft 24 by a tie bar 40, and said arms 39 are formed with integral downwardly directed pointed hooks 41, forming an alined set of spiked devices adapted to enter the sugar cane in the chute from above.

35 Suspended through a loose joint 42, from a bracket 43, located at the transverse center of the chute bottom, is a hydraulic cylinder 44 of the usual type, which is connected at its opposite ends as at 45 and 46, through flexible steel hose 47 and suitable piping 48 and 49 to a four way hydraulic valve 50, having inlet and outlet pipes 51 and 52 respectively and an operating handle 53.

The piston rod 54 of the hydraulic piston 45 44, is pivotally connected as at 55, to a short arm 56, formed with the arm 34' constituting the central arm of the 34 group above described.

50 As above stated, the pins 36 on the arms 34 are pointed as are the hooks 41, and in the claims I shall at times refer to these parts as "spiked", meaning pointed, and further, I may in the claims, for better identification, refer to the arms 27 and 31, of the upper and 55 lower shafts 24 and 33, as "crank-arms".

What I claim and desire to secure by Letters Patent is:

1. In combination with a cane mill having a chute and a conveyor for delivering cane 60 to said chute; cane retarding devices normally located above and beneath the cane mass in said chute; and means for causing said devices to engage and enter the top and bottom layers of said cane mass simultaneously.

2. In combination with a cane mill having a chute, crusher rolls and a conveyor for delivering cane into said chute; cane retarding devices normally located above and beneath the cane mass in the chute, consisting of spiked elements and means for simultaneously causing said elements to enter the upper and lower layers of said cane mass.

3. In combination with a cane mill having a chute and means for feeding cane into said chute; cane retarding devices normally located above and beneath the cane mass in said chute, said devices being interconnected for opposed movements and means for operating said devices to cause them to engage the layers at the top and at the bottom of said cane mass.

4. In combination with a cane mill having a chute, crushing rolls and a conveyor for feeding cane into said chute, cane retarding means operable to engage the cane, close up to and forwardly of the crushing rolls, said means consisting of sets of spiked devices, one set normally located above and the other beneath the cane and extending through the floor of said chute, and means for operating said devices for the purpose set forth.

5. In combination with a cane mill having a chute, crushing rolls and a conveyor for feeding cane into said chute, cane retarding means operable to engage the cane, close up to and forwardly of the crushing rolls, said means consisting of sets of spiked devices, one set normally located above and the other beneath the cane and extending through the floor of said chute, and interconnected means for operating said devices simultaneously.

6. In combination with a cane mill having a chute, crushing rolls, and a conveyor for feeding sugar cane into said chute; a cane leveling device located near the mouth of the chute; cane retarding means located close up to and forwardly of said crushing rolls, said means comprising a set of spiked elements normally held above the cane in the chute, a set of spiked elements operable through the floor of said chute; and means for moving the said elements into engagement with the cane mass simultaneously.

7. In combination with a cane mill having a chute, crushing rolls, and a conveyor for feeding sugar cane into said chute; cane retarding means located close up to and forwardly of said crushing rolls, said means comprising a set of swinging spiked elements normally held above the cane in the chute, a set of reciprocating spiked elements operable through the floor of said chute; and power means for moving the said elements into engagement with the cane mass simultaneously.

8. In means for stopping the feed of sugar cane to the crushing rolls, the combination with an inclined chute through which the

- cane feeds by gravitation; a rock shaft extending across said chute near its top; a plurality of arms rockable with said shaft, said arms having downwardly bent spiked ends, 5 a second shaft extending across under said chute, bearings in which said second shaft may rock; a plurality of arms rockable with the second shaft; spiked pins pivoted to the ends of the last named arms and operable through holes in the bottom of said chute; 10 connections between said shafts; and power means for operating said arms simultaneously to cause the spiked elements to enter the top and bottom layers of said cane.
- 15 9. In cane stop mechanism, in combination with a chute for a sugar mill and a conveyor to feed sugar cane into said chute; an upper horizontal shaft extending across the chute and rockable in bearings at the sides thereof 20 near the top, a sleeve pinned to said shaft, a plurality of arms extending rearwardly from said sleeve and formed with down-bent spiked portions, a tie rod connecting the arms to brace them, a backwardly extending crank- 25 arm fixedly connected to an extended end of said upper shaft; a lower horizontal shaft extending across under said chute; hanger bearings for said shaft; a forwardly extending crank-arm fixed to an extended end of 30 said lower shaft, a link connecting the ends of said crank-arms, a plurality of arms rearwardly directed from and fast with the lower shaft, the central arm of this group having a downward extension, spiked pins pivoted 35 to the ends of these last named arms, the pins operable through holes in the bottom of said chute; a power cylinder having a piston provided with a rod pivotally connected to said downward extension through which the 40 lower shaft is rocked; a four way valve having an operating handle; and piped connections with said cylinder and said valve for operating the said mechanism.
10. In combination with a cane chute and 45 a conveyor to feed sugar cane into said chute; mechanism supported entirely by said chute, and consisting of a spiked device capable of oscillatory movements into and out of contact with the top layers of the cane in said 50 chute; and a plurality of spiked devices capable of reciprocatory movements into and out of engagement with the bottom layers of said cane and power means for operating said devices.
- 55 11. The combination in a sugar mill with a chute and a conveyor to feed cane into said chute, a stop device arranged to oscillate over and into contact with the upper layers of said cane in the chute, plunger stop devices 60 operable through holes in the floor of said chute to engage the lower layers of the said cane and power means for operating said stop devices.
- 65 12. In a stop mechanism, the combination 66 with a chute in a sugar mill and a conveyor
- for feeding sugar cane to said chute, of an oscillatory device having spikes, arranged to assume a normal substantially horizontal position over the cane in said chute, a plurality of spikes operable through a transverse row 70 of holes in the bottom of said chute, and power means located centrally under said chute and connections for causing said spikes to engage the upper and lower layers respectively of the cane mass in said chute.
- Signed at New York, in the county of New 75 York and State of New York, this 19th day of August, A. D. 1930.
